UNITED STATES PATENT OFFICE.

GEORGE BENHAM AND MARTIN A. O'MARA, OF ST. LOUIS, MISSOURI; SAID BENHAM
ASSIGNOR TO SAID O'MARA.

CIGAR LIGHTER.

Application filed December 6, 1917. Serial No. 205,851.

To all whom it may concern:

Be it known that we, GEORGE BENHAM and MARTIN A. O'MARA, both citizens of the United States, and residing at St. Louis, in the State of Missouri, have invented a certain new and useful Improvement in Cigar Lighters, of which the following is a specification.

This invention relates to lighters, and more particularly, to cigar lighters.

In that class of lighters in which the light is furnished by a wick and a highly volatile fuel, such as benzine, naphtha, or gasoline, and where the wick is ignited by an igniting mechanism, the ignition of the wick is often interfered with by air currents which blow out the sparks before they can reach the wick, or which blow the sparks formed, away from the wick. It is, therefore, necessary to either locate the igniting mechanism very close to the wick, which results in a liability of the pyrophoric substance becoming wet by the fuel, thereby interfering with its operation, or it is necessary to make the igniting mechanism of unduly high power. In either case, however, a draft is still liable to prevent the proper formation of sparks, or at least render the ignition of the wick uncertain and spasmodic. Moreover, this draft is liable to interfere with the flame, preventing it from remaining steady, as it should be in order to perform its proper utility as a lighter.

One of the objects of this invention, therefore, is to provide a wind shield which will shield and protect the igniting mechanism so as to prevent interference with the formation and kindling of a proper igniting spark or sparks.

Another object of this invention is to provide a lighter in which the igniting mechanism, as well as the wick, are shielded against air currents, thereby not only promoting the proper ignition of the wick, but also maintaining the lighting flame steady.

Another object is to provide igniting mechanism which is simple in construction, effective in its action, and cheap to manufacture.

Further objects will appear from the detail description taken in connection with the accompanying drawing, in which:

Figure 1 is a side elevation of a lighter embodying this invention;

Figure 2 is a plan, with the shield removed, and with the top supporting part cut away to show the interior section;

Figure 3 is a section on the line 3—3, Figure 2;

Figure 4 is a detail of the igniter mechanism in one of its positions;

Figure 5 is a view similar to Figure 4, but showing the igniter mechanism in another position; and,

Figure 6 is a detail of the retainer.

Referring to the accompanying drawing, 1 designates a base upon which is mounted a fuel reservoir 2 adapted to receive suitable fuel, such as naphtha, and provided with a plug 3 whereby this reservoir may be filled. 70 Mounted on this reservoir is a support 4 upon which is mounted the mechanism embodying this invention.

The igniter mechanism is mounted on the support 4 between a pair of plates 5 and 6 which carry the igniter mechanism as a unit. Projecting through these plates is a wick tube 7. Mounted adjacent the wick tube and on the plate 6 is a hollow threaded tube 8 adapted to receive a suitable pyrophoric substance 9 which is pressed against a milled wheel or element 10 mounted for rotation on the plate 6. The pyrophoric substance 9 is pressed against the milled wheel 10 by a spring (not shown) in the tube, bearing at one end against the pyrophoric substance and at its other end against the closed end of a knurled sleeve 11 threaded on the tube 8. By adjustment of the sleeve 11, the tension of the spring can be adjusted, and by its removal, the pyrophoric substance can be removed or replaced.

The shank of the knurled wheel 10 has attached thereto a ratchet 12 which is engaged by a pawl 13 pivoted on a plate 14 which is in turn pivoted concentric with the axis of the knurled wheel 10. A spring 15 rotates the pawl 13 in engagement with the ratchet 12. The end 16 of the plate 14 is engaged by a retainer 17 having a shoulder 18 in the path of and engaged by the end 16 of the plate 14 and attached at one end to the support 4. This retainer is in the form of a leaf spring which is adapted to be moved on this point of connection so that it may be thrown out of engagement with the end 16 of the plate 14 to release the same as herein-after described.

The retainer 17 has a projecting end 19 arranged in the path of a cam 20 and a plate 21 pivoted concentric with the plate 14. A spring 22 yieldingly connects the arms 23 and 24 on the plates 14 and 21. While the plate 21 has another arm 25 connected by the spring 26 with a post 27 on the support 4, a stop 28 on the plate 21 bears against the plate 14.

- 10 An arm of the plate 21 has a downwardly projecting pin 29 arranged in the path of a lug 30 on a resilient handle 31 projecting through a slot in the support 4 and fixed at its lower end 32 to the reservoir 2. The 15 plate 14 carries a snuffing element 33 adapted to move to positions over and clear of the wick tube 7 as hereinafter described.

Assuming the parts to be in the position shown in Figure 2, at which the time the 20 snuffing element 33 is in a position over the wick and at which time the shoulder 18 of the retainer 17 is in the path of the end 16 of the plate 14, which at this time is held in position by the spring 26 acting through the 25 plate 21 and the stop 28; inward movement of the handle 31 will operate by engagement of the lug 30 with the pin 29 to move the plate 21 in the direction of the arrow thereon (Figure 4) against the tension of the 30 spring 26. This will tension the spring 22 connecting the plate 21 with the plate 14 and will, therefore, place this plate 14 under tension, tending to move it in the direction of the arrow thereon. Movement of the 35 plate 14 is, however, prevented by the engagement of the shoulder 18 of the retainer 17 with the end 16 of the plate 14. As the movement of the plate 21 in the direction of the arrow is continued, the cam 20 thereon 40 will engage the projecting end 19 on the retainer so as to move it out of the path of the end 16 of the plate 14, as shown in Figure 5. As soon as the shoulder 18 clears the end 16, the tension spring 22 will move the plate 14 45 in the direction of the arrow, Figure 5 carrying with it the pawl 13 which at this time engages the ratchet 12 until the plate 14 is stopped by engagement with the stop 28 on the plate 21. This will impart to the 50 knurled wheel 10 a quick movement with respect to the pyrophoric substance 9 bearing there-against, with the result that a shower of sparks will be thrown over the wick in the burner tube 7 so as to ignite this wick, and produce a flame. It will, of course, be 55 understood that during such movement of the plate 21, the snuffer 33 carried thereby has moved clear over the wick tube 7 and makes a shower of sparks. When the handle 60 31 is again released, it will be returned on account of the inherent resiliency, and the spring 26 will return the plate 21, and this plate 21 will, through the engagement of the stop 28 with the plate 14, return this plate to 65 normal position, as shown in Figure 4, with

the shoulder 18 of the retainer again in front of the end 16 of the plate 14. It will, of course, be understood that upon the return movement of the plate 14, the pawl 13 carried thereby will move idly with the ratchet 12. The snuffer 33 will, of course, return with the plate 21 to a position over the wick tube so as to snuff the ignited wick.

Mounted on the support 4 in any suitable manner is a shield 40 preferably in the form of a shell or cup which has a flange 41 frictionally engaging a flange 42 on the support 4. To lock the shield in position, the flange 41 is provided with a pair of pins 43 engaging a bayonet slot 44 in the flange 42. This shield envelops and extends over the burner and the igniting mechanism therefor, and has top openings which, when the shield is in place, are positioned directly over the burner and its wick so as to permit the 85 flame from the burner to issue therethrough. The support 4 is provided with a series of draft openings 46 for purposes hereinafter described.

The provision of the shield prevents interference of drafts or air currents with the igniter mechanism. The igniter mechanism is, therefore, always enabled to throw its sparks across the wick and ignite the same. After the wick is lit, the air currents will 90 not interfere with it, but will rather promote the formation of a steady flame in view of the provision of draft openings 46, which on account of their position and the position of the flame, the openings 45 cause, by the rising heated air currents, a gentle draft to pass upward through the openings 46 and the opening 45, and since these air currents will be uniform and in an upward direction, they will cause the flame from the wick to 95 be directed upwardly, even though a considerable draft may pass those openings of the device. This shield, therefore, not only prevents interference of air currents or drafts with the ignition of the wick, but also permits the maintenance of the burner in the 100 best possible condition.

While this invention is shown as applied to a cigar lighter, it is obvious that it is of 105 advantage for use in various forms of lighters, irrespective of the particular construction or function of the lighter, or the particular construction of the igniting mechanism. It is further obvious that various changes may be made in the details of construction without departing from the spirit of this invention; it is, therefore, to be understood that this invention is not to be limited to the specific construction shown and described.

Having thus described the invention, what is claimed is:

1. A cigar lighter, comprising, a burner, igniter mechanism adapted to kindle said burner and including a movable element,

- means for retaining said element against movement, an actuator yieldingly connected with and adapted to tension said element, during the initial movement of said actuator and while said element is so retained, means carried by said actuator adapted to thereafter operate said retainer to release said element, and a snuffer carried by said element.
- 10 2. A cigar lighter, comprising, a burner, pyrophoric igniter mechanism adapted to generate sparks to kindle said burner and a wind shield for said burner and said lighter mechanism comprising a plate provided with a series of perforations near its periphery mounted on the lighter, and a shell removably mounted on said plate, said shell enveloping and extending over said burner and said igniter mechanism and having a top opening for the flame from said burner, whereby interference of air currents with the formation of and with the kindling action of the sparks is prevented.

In testimony whereof we affix our signatures this 28th day of November, 1917.

GEORGE BENHAM.
MARTIN A. O'MARA.
